METHOD OF REPAIRING, WIDENING, AND
RESURFACING CONCRETE ROADS

John Warren Isett, Hinsdale, Ill.

Application June 17, 1933, Serial No. 676,243

3 Claims. (Cl. 94—4)

This invention relates to a novel and efficient method of repairing, widening and resurfacing concrete roads.

The object of the invention is to provide a method whereby new concrete may be anchored to existing parts of a concrete road in the processes of widening, repairing and resurfacing of such roads, without the necessity of excavating under the existing concrete road and pouring concrete under the exposed portion to form a base for holding the new section against the old concrete. The advantages of my improvement include greatly reduced cost and increased efficiency. The cost of labor required to dig back under the old road and the cost of the additional concrete required to fill in under the old concrete are saved.

Another object is to devise a method for accomplishing the purposes stated, whereby the durability of the road is greatly enhanced, sagging of the new sections is obviated, and pulling away of the new from the old concrete is avoided.

Other objects and advantages will appear from the following description of my invention.

25 In the drawings:

Fig. 1 shows a section of a concrete road which has been widened, and one form of anchoring device for use in widening roads by my process, the view being taken on the line 1—1 of Fig. 2.

30 Fig. 2 is a plan view, on a smaller scale than Fig. 1, of a concrete road which has been widened by the addition of new concrete by my method.

Fig. 3 is a vertical sectional view of a curb to which has been anchored a road section.

35 Fig. 4 is a view similar to Fig. 3, showing a concrete road to which a gutter has been anchored by my method.

Fig. 5 is a perspective view showing the use of my method in repairing a concrete road.

40 Fig. 6 is a plan view of a concrete road in process of being widened and resurfaced by my method, and Fig. 7 is a vertical section of the same, taken on the line 7—7 of Fig. 6.

In that embodiment of my invention shown 45 in Figs. 1 and 2, the existing or old concrete road to be widened is indicated at 10 and the new section at 11. A cylindrical hole 12 is bored in the edge 13 of the old concrete 10, preferably but not necessarily about midway between the top

50 surface 14 and the bottom 15. An anchoring device is positioned in the hole 12 and firmly fixed therein. I preferably employ expansion bolts for this purpose, one example of which is shown in the drawings and comprises a bolt 16 with hook end 55 17, head 18, lead alloy sleeve 19 and hard metal

cone 20. The bolt 16 carrying the sleeve 19 and cone 20 is inserted into the hole 12, head first, and by means of a suitable tool (not shown) the cone is forced into the sleeve, thereby expanding the sleeve and causing it to be firmly wedged against the walls of the hole 12. The bolt and hook end 17 protrude from the hole 12 in the concrete 10 any desired length.

It will be understood that the anchoring device shown and described is only one of many which may be used. Hard metal bolts, either straight or hooked, having smooth or deformed surfaces, and held in position by either hard or soft metal or jute composition sleeves and cones, may be used. In fact, any device having the required 65 rigidity and strength, provided with means for fastening it to old concrete, and projecting from said old concrete, may be used in practicing my method of widening, repairing and resurfacing 70 concrete roads.

Preferably the anchoring devices 16 used in practicing my method of widening old concrete roads have ends 17 forming hooks of 180° bend, and are fixed in holes 12 spaced about four feet 80 apart in the side edge of the old concrete.

After the anchoring means has been fixed to the old concrete, the next step, preferably, is to place a reinforcing rod 21 on the protruding portions of the bolts 16. When a hooked form of anchoring device is used the rod 21 may be conveniently held by the hooked portion 17 as shown in the drawings. Other reinforcing means may also be associated with the anchoring devices, as for example, wire or expanded metal mesh or 90 mats.

Finally the new concrete 11 is poured onto the foundation adjacent the old concrete. If no expansion joints are used between the new and the old concrete, the new will become an integral part 95 of the old, and, either with or without expansion joints, the new section will be tied to the old in such manner that it will not sag or pull away from the old.

In Fig. 3 is shown the use of my process in connection with a curb 22 and new concrete section 100 23, the anchoring device being similar to that heretofore described. Fig. 4 illustrates the use of the process in anchoring a new gutter 24 to the old concrete road 25.

The process of repairing a concrete road is 105 illustrated in Fig. 5, in which the old concrete 26 has a hole defined by the edges 27. Cylindrical holes are bored in the edges 27, as heretofore explained, and anchoring devices are fixed therein so as to protrude into the area to be repaired. 110

In this embodiment I prefer to use expansion bolts 28, having ends 29 at right angle to the bolt shank, and in the same horizontal plane as the shank of the device. However, other anchoring means

5 may be substituted. Reinforcing rods, mesh or mats may be supported on the protruding parts of the anchoring devices, if desired. New concrete is poured into the space between the edges 27, covering the anchoring devices, and when the 10 same has become rigid, the new section will be firmly anchored to the old, and will remain in its proper horizontal plane relatively to the old concrete.

In Figs. 6 and 7, the use of my process for 15 widening and resurfacing a concrete road is illustrated. Cylindrical holes are bored in the top of the old concrete road 30 and also in the edge at the side to be widened. Expansion hook bolts, 90° bend, indicated at 31 are preferably positioned in the holes formed in the top surface of the concrete 30, usually arranged on thirty inch centers. Expansion hook bolts 32 with curved hook ends 33, such as heretofore described, are 20 preferably used in the side edge, usually four feet apart. Reinforcing mesh 34 is supported by and anchored to the bolts 31, short tie wires being preferably used for tying the mesh 34 to the bolts 31, and similar mesh or other reinforcing means 25 35 is connected to the hook bolts 32 at the side of the old concrete. If desired, the mesh 34 may extend over the side edge of the old concrete and serve to reinforce the widened section.

New concrete 36 is then poured on the top surface of the old concrete 30 and on the foundation 35 adjacent the side edge, to the desired height and width, covering the bolts 31, 32 and the reinforcing mesh 34, 35. The old road 30 is thus widened and resurfaced by new concrete 36 which becomes

an integral part of the old and is firmly anchored thereto and prevented from sagging and separating.

I claim:—

1. The method of widening and repairing concrete roads without digging back under the old concrete, which comprises boring a plurality of horizontally spaced apart holes in the edge of the existing concrete road, securing an anchoring device in each hole with one end of the anchoring device protruding from the hole, and pouring new concrete adjacent the edge of the old to a desired height and width and to cover the anchoring devices. 80

2. The method of widening and repairing concrete roads which comprises boring a plurality of horizontally spaced apart holes in the edge of the existing concrete road, securing a hooked end expansion bolt in each hole, with the hooked end protruding from the hole, placing a reinforcing rod on the shanks of the expansion bolts, within the hooked ends, longitudinally of the road edge, and pouring new concrete adjacent the edge of the old to a desired height and width and to cover said expansion bolts and reinforcing rods. 85

3. The method of widening and repairing concrete roads which comprises boring a plurality of horizontally spaced apart holes in the edge of the existing concrete road, securing a hooked end expansion bolt in each hole, with the hooked end protruding from the hole, attaching reinforcing mesh to the expansion bolts and arranging the mesh in a substantially horizontal plane across the area to be widened, and pouring new concrete adjacent the edge of the old concrete to a desired 100 height and width and to cover said expansion bolts and mesh. 105

JOHN WARREN ISETT.
